US0D1038118S

(12) **United States Design Patent** (10) Patent No.: **US D1,038,118 S**
(45) Date of Patent: ** Aug. 6, 2024

(54) **SMARTWATCH**

(71) Applicant: **SHENZHEN DO INTELLIGENT TECHNOLOGY CO., LTD.**, Shenzhen (CN)

(72) Inventors: **Yanxiong Zhu**, Guangdong (CN); **Beijie Hong**, Guangdong (CN)

(73) Assignee: **SHENZHEN DO INTELLIGENT TECHNOLOGY CO., LTD.**, Shenzhen (CN)

(**) Term: **15 Years**

(21) Appl. No.: **35/516,481**

(22) Filed: **Jan. 18, 2023**

(80) **Hague Agreement Data**

Int. Filing Date: **Jan. 18, 2023**

Int. Reg. No.: **DM/226937**

Int. Reg. Date: **Jan. 18, 2023**

Int. Reg. Pub. Date: **Mar. 3, 2023**

(30) **Foreign Application Priority Data**

Nov. 18, 2022 (CN) 202230771312.8

(51) **LOC (14) Cl.** **14-02**

(52) **U.S. Cl.**

USPC **D14/344; D10/70; D24/167; D24/186**

(58) **Field of Classification Search**

USPC ..... D14/138 R, 344; D10/30-32, 38, 70, D10/128, 132; D11/3; D24/167, 186

(57) **CLAIM**

The ornamental design for a smartwatch, as shown and described.

DESCRIPTION

1. Smartwatch
- 1.1 : Front
- 1.2 : Back
- 1.3 : Left
- 1.4 : Right
- 1.5 : Top
- 1.6 : Bottom
- 1.7 : Perspective
- 1.8 : Perspective

1 Claim, 8 Drawing Sheets
